MASS SPECTROMETER

William H. Wells and William C. Wiley, Detroit, Mich., assignors to Bendix Aviation Corporation, Detroit, Mich., a corporation of Delaware

Application October 15, 1951, Serial No. 251,352

10 Claims. (Cl. 250—41.9)

This invention relates to mass spectrometers and more particularly to mass spectrometers for, and methods of, distinguishing between the masses of different ions by measuring their times of flight. The invention is especially adapted to provide a relatively sharp differentiation between ions of different masses.

In some mass spectrometers now in use, pulses of ions are formed from the different molecules of gas in an unknown mixture and are subjected to a predetermined force so as to be accelerated through a predetermined distance. The ions of relatively light mass are given a greater acceleration by the predetermined force than the ions of heavy mass and are collected at the end of the predetermined distance before the ions of heavy mass. Thus, by measuring the times required for different ions in the pulse to travel through the predetermined distance, the masses of the ions can be determined.

Difficulties in measurements arise in the spectrometers now in use and prevent the measurements from being as accurate and meaningful as might be desired. For example, since the finite width of the pulse may cause individual ions of a given mass to be located at different positions in the pulse before the ions are accelerated towards the collector plate, all ions of the given mass are not collected at the same time. In addition, the thermal and other energy of the ions imparts a random motion to the ions before the application of any external force so that some ions of a given mass are moving towards the collector plate at the time that the predetermined force is imposed and other ions of the same mass are moving away from the collector plate at that instant. Thus, the thermal and other energy of the ions also prevents all ions of a given mass from being simultaneously collected in spectrometers now in use.

This invention provides a mass spectrometer in which errors resulting from the different positioning and random motion of individual ions are minimized. The errors are minimized by the utilization of an accelerating grid having an extended width and by the disposition of the collector plate at a predetermined distance from the starting point of the ions.

An object of this invention is to provide a mass spectrometer for distinguishing between ions of different mass by measuring the time required for the ions to travel through a predetermined distance.

Another object is to provide a mass spectrometer of the above character for providing a relatively sharp differentiation between ions of different mass.

A further object is to provide a mass spectrometer of the above character utilizing an accelerating grid having an extended width so as to improve the response characteristics of the spectrometer.

Still another object is to provide a mass spectrometer of the above character having a collector plate disposed at a predetermined distance from the grid to improve the response characteristics of the spectrometer.

A still further object is to provide methods of the above

2

character for providing a relatively sharp differentiation between ions of different mass.

Other objects and advantages will be apparent from a detailed description of the invention and from the appended drawings and claims.

In the drawings:

Figure 1 is a view illustrating somewhat schematically the mechanical and electrical features constituting one embodiment of the invention, the mechanical features being shown in perspective and some of the electrical features being shown in block form;

Figure 2 is an enlarged sectional view of the grid structure constituting a part of the embodiment shown in Figure 1, the section being taken substantially on the axis of the structure; and

Figure 3 is a schematic perspective view illustrating somewhat schematically another embodiment of the invention.

In the embodiment of the invention shown in Figure 2, 1, a cathode 10 made from a wedge-shaped strip of a suitable material such as tungsten is provided. A control grid 12 is disposed relatively close to the cathode 10 and is provided with a vertical slot 14 whose median position lies in substantially the same horizontal plane as the cathode. An accelerating grid 16 is positioned relatively close to the control grid 12 on one side and to a shield grid 18 on the other side and is substantially in alignment with both grids. Vertical slots 20 and 22 corresponding substantially in shape and position to the slot 14 are provided in the grids 16 and 18, respectively.

A vertically disposed backing plate 24 is provided to the rear of the slots 14, 20 and 22 and substantially in parallel with the flow of electrons from the cathode 10 through the slots. A non-conductive container 26 having a relatively great axial length and a relatively small width extends in a horizontal plane from the plate 24. The container 26 preferably has a circular cross-section in a direction perpendicular to its axis but may have other sectional configurations, such as a square cross-section.

Bores 28 are provided in the container 26 substantially in alignment with the median positions of the slots 14, 20 and 22. The bores 28 serve to provide a passageway for the flow of electrons transversely through the container 26 to a collector plate 29 positioned on the far side of the container substantially in parallel with the grids 12, 16 and 18. A grounded conductive sleeve 30 having holes corresponding in position to the bores 28 fits on the container 26. The sleeve 30 eliminates any

effects from electrical charges which result when electrons from the electron stream impinge on the container instead of passing through the bores. Holes 31 are also made in the bottom of the container 26 and the sleeve 30 substantially in the same plane as the bores 28 to provide for the introduction of gas through a conduit 32.

55 The conduit in turn extends from a receptacle 34 adapted to hold molecules of the different gases constituting an unknown mixture.

A plurality of conductive grids 36 made from a suitably meshed material extend at spaced intervals across the bore in the container 26 substantially in perpendicular relationship to the axis of the container. The grids 36 are secured at their peripheries to rings 38 which fit snugly in the container 26 and which have an extended axial length such that the end of one ring is contiguous to the opposite end of the adjacent ring. Successive grids are adapted to receive voltage pulses of progressive amplitude from a pulse forming circuit 40. For example, if five grids are provided at spaced intervals along the container, a positive pulse of 150 volts may be applied to the backing plate 24 and positive pulses of 120, 90, 60 and 30 volts may be respectively applied to succes-

70

sive grids. The grid furthest removed from the plate 24 may be grounded.

A collector plate 42 is positioned substantially parallel to the plate 24 and grids 36 at a distance from the end of the container 26 approximately twice as great as the length of the container itself. A time indicator 44 such as an oscilloscope, is connected to the collector plate 42 to indicate the relative times at which the ions of different mass arrive at the collector plate. Since the collector 42 actually serves as an ion detector, other types of detectors may be used.

In the steady-state condition, the control grid 12 and the accelerating grid 16 have positive voltages applied to them from suitable output terminals of a direct power supply 46, and the collector plates 29 and 42 have slightly positive voltages applied to them from other terminals of the power supply. The cathode 10, the shield grid 18, the backing plate 24 and the grids 36 are substantially at ground in the steady-state condition.

Because of the positive voltage on the grid 12 relative to the voltage on the cathode, electrons emitted by the cathode are accelerated towards the grid in the steady-state condition. The electrons are not accelerated beyond the grid 12, since the grid 16 has approximately the same positive voltage as the grid 12, and the grid 18 is substantially at ground. As a result, any electrons which pass through the bores 28 in the container 26 do not have sufficient energy to ionize molecules of gas introduced into the container through the conduit 32.

At predetermined times, negative voltage pulses of substantially equal magnitude are applied to the cathode 10 and the control grid 12 from the pulse forming circuit 40. Since the grid 12 is still more positive than the cathode 10, the electrons emitted by the cathode continue to be attracted towards the grid. The electrons are further considerably accelerated in the region between the grids 12 and 16 because of the positive voltage which exists on the grid 16 relative to the voltage on the grid 12 during the pulses. The additional acceleration imparted to the electrons by the grid 16 causes the electrons to travel through the bore 28 into the container 26 with sufficient energy to ionize some of the gas molecules introduced into the container.

Because of their positive charge, the ions produced by the collision between electrons and gas molecules are retained within the negative field created by the stream of electrons flowing towards the collector plate 29. By retaining the ions within the electron stream, a pulse of ions having a relatively narrow width is obtained. The electron stream is relatively narrow because of the collimating action provided by the slots 14, 20 and 22 and the collimating action which may be provided by a suitable magnetic field (not shown).

In addition to producing an ion pulse having a relatively narrow width, the relatively large charge of the negative field causes the number of ions forming the pulse to be considerably increased over the number of ions comprising a pulse in spectrometers now in use. The creation of an ion pulse having a relatively narrow width and a relatively large number of ions produces an increase in the sensitivity with which the mass spectrometer responds to ions of different mass. The formation of the electron stream and the retention of ions within the stream are disclosed in detail in co-pending application Serial No. 221,554, filed April 18, 1951, by Ian H. Mc Laren and William C. Wiley, now Patent No. 2,732,500.

The ions retained within the negative field are produced during the application of the negative pulses on the cathode 10 and grid 12. At approximately the same time as the negative pulses on the cathode 10 and grid 12 are discontinued or at a slightly later time, positive pulses are applied to the backing plate 24 and the grids 36. Equipment for producing a pair of pulses separated from each other by a relatively short time is well known

to persons skilled in the art and may be either purchased or built. For example, the Berkeley Scientific Company of Richmond, California, manufactures equipment for producing a pair of pulses which may be separated from each other by a variable period of time dependent upon the adjustment of a knob. This equipment is designated by Berkeley as Model 902 of its double pulse generator. If it is not desired to purchase equipment which provides a pair of pulses separated from each other by a variable period of time, such equipment may be built in accordance with principles outlined on pages 223 to 238, inclusive, of volume 20 entitled "Electronic Time Measurements" of the Radiation Laboratory Series prepared by the Massachusetts Institute of Technology.

The voltage pulses on the plate 24 and the grid 36 cause the ions to be accelerated through the container 26 towards the collector 42. Since the ions of relatively light mass are accelerated more by the predetermined forces applied by the grids 36 than the ions of heavy mass, they reach the collector plate 42 before the ions of heavy mass. By measuring the times at which the different ions reach the collector plate, the masses of the ions can be determined.

We have found that, in spite of the narrow width of the ion pulse, errors in measurement result in spectrometers now in use from the different disposition of individual ions in the ionization region. For example, some ions of a given mass may be located spatially at the back of the pulse and other ions of the same mass may be positioned at the front of the pulse. This causes individual ions of a given mass to arrive at the collector plate before other ions of the same mass and clouds the measurements which are obtained.

Errors in measurement also result in spectrometers now in use from the random motion imparted to the ions by the thermal and other energy of the ions before the application of any external forces. For example, some ions of a given mass may be moving towards the collector plate at the instant that a voltage pulse is applied to the ion accelerating grid, and other ions may be moving away from the collector plate at that instant.

We have also found that the errors resulting from the different positioning and the random motion of individual ions can be minimized if the collector plate is placed at a predetermined distance from the accelerating grid. This distance has been found by analysis to be approximately twice the distance between the grid and the ion pulse before the pulse is accelerated towards the grid when the ion pulse has a relatively narrow dimension in the direction of the grids 36. For increased lengths of the ion pulse, the position of focus is given as

$$Q = 2\sqrt{S_1 S_2}$$

where:

55 Q =the position of optimum ion focus;
 S_1 =the distance from the last grid 36 to the end of the ion pulse nearest the backing plate 24;
 S_2 =the distance from the last grid 36 to the end of the ion pulse most removed from the backing plate 24.

60 The term "focussing" as used herein refers to the action of bringing the ions of each mass together into relatively tight groups in the direction of their movement. As such, the term "focussing" refers to the action of bunching the ions of each mass in the direction of their movement so that they are collected in a minimum amount of time. Since the distance between the pulse and the grid is relatively small, the distance between the grid and collector plate is also small. This short distance prevents ions of different mass from becoming sufficiently resolved in space before they reach the collector plate and causes the spectrometer to give somewhat inaccurate results.

This invention focusses the ions of each mass in the direction of their travel by disposing a detector such as the collector 42 at a position approximately twice as

far away from the last grid 36 as the distance between the electron stream and the last grid. The invention also produces a material separation between the ions of different mass by effectively increasing the length of the accelerating region. This is accomplished by providing a plurality of equally spaced grids 36 and by applying voltage pulses of progressively decreasing amplitude between successive pairs of grids. The ions then move through the grid with a substantially constant acceleration. Because of the substantially constant acceleration imparted to the ions, the grids in effect provide an electrical field having a substantially constant intensity over an extended width. This in turn causes the distance between the end of the last grid 36 and the collector plate 42 to be considerably increased in order to obtain a distance which is approximately twice the distance between the ion pulse in its stationary position and the last grid 36.

Because of the extended length of the electrical field and the distant positioning of the collector plate 42, the ions require at least as long a time to reach the collector plate as in the spectrometers now in use. By placing the collector plate at the optimum distance from the last grid 36 without reducing the time of ion travel, ions of a given mass are focussed in space better than in spectrometers now in use. This in turn causes the sharpness and accuracy of the measurements obtained to be considerably increased.

Since the ultimate object is to obtain an electrical field which is substantially constant over an extended length, the operation of the grid structure shown in Figure 1 can probably be enhanced by increasing the number of grids and correspondingly decreasing the distances and voltages between them. The grid structure may also be used so that rings similar to the ring 38 are used without any wire mesh.

It should be realized that other structures than that disclosed above may be used to form a relatively narrow ion pulse for passage through the container 26. It should be realized also that the ions may be accelerated through the container by applying pulses of negative voltage to the different grids. In this way, the ions are attracted towards successive grids rather than being repelled from one grid to the next.

A modification of the invention disclosed above is illustrated in Figure 3. In this embodiment, a container 70 formed from a thin sheath of conductive material is used. The end of the container near the collector plate is grounded and the end of the container near the backing plate is adapted to receive a pulse of positive voltage from a pulse forming circuit 52. Current flows axially along the sheath and produces a voltage which gradually decreases along the axial length of the sheath.

It should be appreciated that the plurality of grids 36 are provided to produce an electrical field of extended length. A field of extended length is produced so that the collector 42 can be positioned a relatively great distance from the backing plate 24.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

What is claimed is:

1. A mass spectrometer, including, means for obtaining a plurality of ions, an ion detector, a grid assembly positioned between the ion-obtaining means and the ion detector to provide a substantially constant acceleration of the ions through a first region equal in distance to substantially one-half the distance between the end of the first region and the detector, and means for indicating the relative times at which the ions of different mass are detected.

2. A mass spectrometer, including, means for obtain-

ing a plurality of ions, an ion detector, a grid assembly positioned between the ion-obtaining means and the detector and having an extended length in the direction of the detector equal to substantially one-half the distance between the end of the grid assembly and the detector, means for producing an electric field through the extended length of the grid assembly to provide a constant acceleration on the ions, and means for providing an indication of the relative times at which the ions of different mass are detected.

3. A mass spectrometer, including, means for obtaining a plurality of ions, an ion detector, a grid assembly positioned between the ion-obtaining means and the detector and equal in distance substantially to one-half the distance between the end of the grid assembly and the detector, means for applying voltage pulses of predetermined magnitude on the grid assembly to produce a substantially constant acceleration of the ions through the grid assembly, and means for indicating the relative times at which the ions of different mass are detected.

4. A mass spectrometer, including, means for obtaining a plurality of ions, means for providing an electric field of substantially constant magnitude through a first region to provide a substantially constant acceleration of the ions through the region, an ion detector positioned at a distance past the end of the first region corresponding to substantially twice the distance of travel of the ions through the region, and an indicator for showing the relative times at which the ions of different mass are detected.

5. A mass spectrometer, including, means for obtaining a plurality of ions, means for providing a substantially linear and constant acceleration of the ions through a first region, an ion detector positioned at a distance past the end of the first region corresponding to approximately twice the distance of ion acceleration through the first region, and means for indicating the relative times at which the ions of different mass are detected.

6. A mass spectrometer, including, means for providing pulses of ions, an ion detector, a grid structure positioned between the ion-providing means and the detector, means for applying voltages to the grid structure to produce a movement of the ions in each pulse towards the detector, the detector being positioned at a distance past the end of the grid structure corresponding to approximately twice the distance of acceleration of the ions by the grid structure, and means for indicating the relative times at which the ions of different mass in each pulse are detected.

7. A mass spectrometer, including, means for obtaining a pulse of ions in a confined region, means for providing an electric field of substantially constant magnitude through a first region to provide a substantially constant acceleration of the ions through the region, an ion detector positioned at a distance past the end of the first region corresponding to substantially twice the square root of the distance from the end of the first region to the remote end of the confined region multiplied by the distance from the end of the first region to the near end of the confined region, and an indicator for determining the relative times at which the ions of different mass are detected.

8. A mass spectrometer, including, means for providing pulses of ions of finite width, an ion detector, a grid structure positioned between the ion-providing means and the detector, means for applying voltages to the grid structure to produce a movement of the ions in each pulse towards the detector, the detector being positioned at a distance past the end of the grid structure corresponding to substantially twice the square root of the distance between the end of the grid structure and the remote end of the ion pulse multiplied by the distance between the end of the grid structure and the near end of the ion pulse, and an indicator for determining the relative times

at which the ions of different mass in each pulse are detected.

9. A mass spectrometer, including, means for providing a plurality of ions, an ion detector, a plurality of grids disposed at spaced intervals between the ion-providing means and the detector, means for applying progressively more negative voltage pulses to the successive grids in the plurality to produce a substantially constant electric field throughout the extended region defined by the grids for movement of the ions past the grids and towards the detector, the detector being positioned at a focal distance past the end of a last grid in the plurality to detect the ions of each mass at substantially the same instant of time, and means for indicating the relative times at which ions of different mass are detected.

10. A mass spectrometer, including, means for providing a plurality of ions, an ion detector, a plurality of grids disposed at spaced intervals between the ion-providing means and the detector to provide an electric field of substantially uniform intensity between the ion-providing means and a last grid in the plurality upon the

5

application of particular voltage pulses to the grids in the plurality, means for applying the particular voltage pulses to the grids in the plurality to produce a movement of the ions past the grids and towards the detector, the detector being positioned at a distance past the last grid equal to substantially twice the distance between the ion-providing means and the last grid, and means for indicating the relative times at which ions of different mass are detected.
